UNITED STATES PATENT OFFICE.

ALLEN BOUCHER, OF ROCHESTER, NEW YORK, ASSIGNOR TO THE CALDWELL MANUFACTURING COMPANY, OF NEW YORK.

GARMENT-HANGER.

SPECIFICATION forming part of Letters Patent No. 662,908, dated December 4, 1900.

Application filed April 17, 1899. Serial No. 713,424. (No model.)

To all whom it may concern:

Be it known that I, ALLEN BOUCHER, a citizen of the United States, and a resident of Rochester, in the county of Monroe and State 5 of New York, have invented certain new and useful Improvements in Garment-Hangers, of which the following is a specification.

This invention relates to garment-hangers, and particularly to such garment-hangers as 10 are adapted to clamp articles of clothing in them, whereby the clamping assists in keeping the form of such articles. This embodiment of my device is adapted to hanging of pantaloons which are supported in it by 15 clamping the lower edges of the legs of the pantaloons between the two parts of the device.

In the drawing, A is the body or main part of the garment-hanger having a lower edge a, 20 that is preferably straight, and B is a strip of suitable material adapted to be held parallel to the lower edge of the body A and to be clamped against the side of said body.

C C are arms pivotally connected to the 25 clamping-strip B and pivotally supported or hinged to the body-piece A. The arms C C are preferably made of one continuous piece of iron having a loop c connecting them, which is normally sprung outward at the middle of 30 its curvature from the body-piece A.

The clamping or pressure arm D is pivoted at d to the body-piece A at a point that is substantially the center of the circle of curvature of the connecting portion c between 35 the arms C C and may be turned so that it presses against the curved connecting-piece c. The plane of the curved piece c is at an angle to the plane of the adjacent face of the body-piece, and as it is farthest from said 40 piece A at its center it follows that as the arm D is turned over the curved piece c said curved piece is compressed more and more as the said arm approaches its center. The arm D, however, may be turned around so

far as to be disengaged entirely from the 45 curved piece c, and in this last position the strip B is released from compression against the body-piece A and may be swung outward therefrom to release any article that may have been clamped between said strip B and 50 the body-piece A. On inserting the lower edges of a pair of trousers-legs between the strip B and the body-piece A the arm D is turned around until it engages upon the curved piece c, whereupon a clamping action 55 will occur wherein the pressure may be increased up to the point where the arm D is in contact with the middle of the curved piece c. This produces a graduated pressure, so that the trousers-legs may be clamped with greater 60 or less force, as may be desired.

The device is adapted to the supporting of trousers made of cloths of different thicknesses without compressing the cloth at the place of compression so far as to mark it permanently. 65

What I claim is—

A garment-hanger consisting of the body-piece A having a strip B along its lower edge, arms C, C, pivotally connected to said strip 70 and to said body-piece and having the curved connecting-piece c integral with said arms, the plane of said curved connecting-piece being at an angle to the plane of the adjacent face of said body-piece, and the rotary pressure-arm D pivoted to said body-piece and adapted to press against said curved connecting-piece so that said connecting-piece moves toward or away from said body-piece and thereby to produce variable pressure of 80 said strip against said body-piece, according to the position of said clamping-arm, substantially as described. 75

ALLEN BOUCHER.
